McLabb & Hinckle, Atty.

UNITED STATES PATENT OFFICE

JOSEPH M. HADFIELD, OF CHICAGO, ILLINOIS

SAFETY DEVICE FOR MOTOR DRIVEN TOOLS

Application filed October 10, 1931. Serial No. 568,196.

The present invention relates to safety devices for motor driven tools and is particularly concerned with the provision of devices for preventing the users of motor driven tools from leaving the usual metal pin which is used for holding the drive shaft while cutters are adjusted, in the shaft when the motor is started.

The present invention is applicable to motor driven tools of various kinds, and therefore the tool is merely illustrated diagrammatically. It is customary in the adjustment of the cutters on many motor driven tools to insert a metal pin in a hole in the drive shaft or in some part of the mechanism for positively preventing rotation of the shaft while the cutters are being adjusted. This permits the more convenient adjustment of the cutters, since the shaft is held in fixed position, and it also prevents any possibility of the shaft rotating the cutters and possibly injuring the operator.

Such metal pins are frequently left in the drive shaft when the operator has adjusted the cutters, and when the motor circuit is closed the motor is burned out due to the fact that its armature cannot rotate and there is no counter-electromotive force to limit or regulate the current in the motor. When this happens, a great deal of expense is involved because the motor must be practically replaced with a new motor and one of the objects of the invention is the provision of a safety system adapted to positively prevent the mistake of leaving the metal pin in the shaft when the motor circuit is closed.

Another object of the invention is the provision of an improved switching device which is adapted to be placed in the circuits of any electric motor for the purpose of controlling the motor circuit by means of the usual metal pin which is employed for holding the shaft in fixed position when the cutters are adjusted.

Another object of the invention is the provision of an improved switching device of the class described which will prevent the operator of a motor driven tool from leaving the metal pin in the drive shaft.

Another object of the invention is the pro-

vision of an improved switching device of the class described which is adapted to be constructed out of ordinary stock materials such as a conduit outlet box and the usual accessories for installing conduits.

Another object of the invention is the provision of an improved switching device of the class described which is sturdy, economical and capable of being manufactured cheaply and capable of performing its functions for a long period of time without necessity for repair.

Other objects and advantages of the invention will be apparent from the following description and from the accompanying drawing, in which similar characters of reference indicate similar parts of the several views.

Referring to the single sheet of drawing,

Fig. 1 is a diagrammatic view of the safety system with the motor circuit in open position;

Fig. 2 is a transverse sectional view taken through the switch casing, showing the switching device in partial section with the switch in closed position.

Fig. 3 is a wiring diagram of another modification.

Fig. 4 is a vertical sectional view taken on the plane of the line 4-4 of Fig. 1, showing the arrangement of the metal pin for preventing rotation of the shaft.

Referring to Fig. 1, the safety system preferably includes an electric motor 10, any form of speed reduction, speed change or speed increasing gearing 11, a drive shaft 12, some form of cutter 13, and a switching device indicated in its entirety by the numeral 14. The mechanism of the motor driven tool may be provided with an aperture 15 in the drive shaft 12 adapted to register with an aperture 16 in the gear casing 11, so that the metal pin 17 may be inserted through the apertures 15 and 16 to hold the drive shaft 12 in fixed position.

The control circuits for the motor preferably include the conductors 18 and 19 leading from the source of current supply and controlled by the double pole switch 20. The conductors 21 and 22 from the motor 10 lead

to the switch 20 and to the switching device 14 respectively, and another conductor 23 leads from the switching device 14 to the double pole switch 20. The switching device 14 is thus included in series with at least one of the conductors leading to the motor 10, so that the motor cannot be operated without closing both the switches 14 and 20, in Fig. 2.

10 The contingency against which the present device is intended to guard is the fact that the users of such machines often closed the switch 20 while the pin 17 was still holding the shaft 12 in fixed position, thereby causing the motor to be subjected to a surge of current which usually burns out the motor.

When the switching device 14 is included in the circuits 18, 21, 10, 22, 23, 19, the motor circuit may be closed at the switch 20 but the motor will not be energized until the pin 17 is removed from the shaft 12 and placed in the socket 24.

Referring to Fig. 2, this is a full size sectional view of the switching device shown diagrammatically in Fig. 1. The casing for the switching device 14 may consist of an ordinary outlet box 25 of the type usually employed with conduit and provided with a number of standard knockouts. The knockouts have been driven out at the points 26, 27 and 28 to adapt the outlet box as a casing for the present switching device.

The socket 24 comprises a metal sleeve having a threaded end 28 which passes through the aperture 26 and is secured to the outlet box by nuts 29, 30 on the inside and outside of the outlet box. The outlet box 25 is preferably so disposed that the metal sleeve 24 extends in a vertical direction so as to slidably receive the pin 17 to permit the pin to actuate the switching device 14 by gravity.

The opening 28 is utilized for receiving the conduit 31 through which pass the conductors 22, 23. The opening 27 may likewise be provided with a metal sleeve 32 secured in place in the casing 25 by nuts 33, 34 and the sleeve 32 provides a support for an insulating tube 35 forming a base for the switch. The tube 35 may be provided with transverse apertures 36, 37 for receiving the screw bolts 38, 39. The screw bolt 39 may be provided with an ordinary head or a copper contact block 40 adapted to serve as a fixed contact, while the nut 41 of bolt 39 serves to provide a connection for the conductor 23.

The screw bolt 38 may be provided with a resilient steel leaf spring 42 having an aperture for receiving the bolt 38, and the leaf spring 42 is preferably provided with a contact block 43, which may be constructed of copper or other highly conductive material. The contacts 40, 43 are not intended to be used in breaking the circuit since the motor 10 will generally have been stopped by means

of the control switch 20 before the pin 17 is removed from the switching device 14, but if desired, the blocks 40, 43 may be made of carbon or other material capable of breaking circuits with relatively large current.

The circuit shown in Fig. 1 is suitable for control of small single phase motors drawing relatively small currents, but when three phase motors drawing larger currents are utilized, it is preferable to use the arrangement shown in the wiring diagram of Fig. 3.

The bolts 38 and 39 are preferably made of brass or copper and a pigtail 44 preferably extends from the contact 43 to the bolt 38 to carry the current and prevent heating of the spring 42 by the motor current. A flexible rubber insulating plate 45 is located above the spring 42 and secured by the bolt 38 for the purpose of insulating the pin 17 from the spring 42 and the motor circuit.

The operation of the present safety system is as follows: When the user of the motor driven tool desires to adjust the cutter or perform any operation which necessitates the use of the metal pin 17, he removes the metal pin from the sleeve 24, thereby permitting the spring 42 to separate the contacts 40, 43 and break the motor circuit. The parts are then in the position of Fig. 1. In some embodiments of the invention the control switch 20 may be eliminated provided the switching device 14 is designed to break heavy currents. In any event, the closing of the control switch 20 cannot start the motor unless the pin 17 is placed in the sleeve 24 in such position as to close the switch 14. The switch 14 being secured on the wall or any adjacent fixed support, it is necessary for the user to remove the pin 17 from the shaft 12 and place it in the sleeve 24, and should he forget to remove the pin he will be reminded to do so by the fact that the motor does not run when the control switch 20 is closed.

Referring to Fig. 3, this is a modification in which the motor 10 is driven from a three phase circuit. The motor is controlled by a starter switch having a magnet coil 50 adapted to actuate an armature 51 which is connected to a plurality of switch arms 52, 53, 54, 55. The switch arms 52, 55, cooperate with fixed contacts 56-59. The contacts 56-58 are connected to the ordinary three phase line, while the contact 59 is connected to contact 57 and to a push button contact 60 by a conductor 61. Contacts 55, 59 are intended to cooperate with a pair of "start" and "stop" push buttons 62, 63 in such manner that the button 62 energizes the magnet 50, while the button 63 de-energizes the magnet 50.

Push button 62 has two fixed contacts 60 and 63'. The fixed contact 63' is connected by a conductor 64 to one end of the magnet coil 50, which is also connected by a conductor 65 to the switch arm 55. Push button

62 is provided with a spring for normally urging it to open position, and it will be noted that when the push button 62 is actuated, a circuit may be traced from the second phase 5 to the third phase, through the magnet 50. The magnet then draws up its armature 51 and closes the starter switch contacts in all three phases, as well as contacts 55, 59.

The other end of the magnet coil 50 is connected by connector 66 to one of the contacts 10 67 of the push button 63. The other fixed contact 58 of push button 63 is connected by conductor 69 in series with the safety switch 14. A conductor 70 leads from the safety 15 switch 14 to the third phase of the three phase line.

Push button 63 is normally urged to closed position by a spring, and it will be observed that the closing of contacts 55, 59 short-circuits 20 the push button 62. When push button 62 is released, therefore, the magnet 50 remains energized until push button 63 is pushed, breaking the magnet circuit and de-energizing the magnet, which results in the 25 release of armature 51 and the opening of the three phase contacts.

It will thus be observed that the present device may also be used with a motor starter in a three phase circuit, or it may be used 30 with motor starters for single phase circuits. Since the safety switch is in series with the main circuit of the magnet coil 50, it is impossible to energize the magnet 50 without placing the pin 17 back in the safety switch 35 box.

It might be thought that the operator could quickly see that the machinery was not moving when he closes the switch 20, thereby reminding him that he has not removed the pin 40 17, but in many cases the mechanism moves so fast that it is difficult to distinguish whether it is moving or standing still, and the failure to remove the said pin 17 in the devices of the prior art almost inevitably results 45 in the burning out of the motor.

When the present device is used, the operator is reminded that the pin 17 must be placed in the switching device 14, and furthermore, a definite place is provided for 50 keeping the pin 17 so that it is not lost.

The present device positively precludes operators from burning out the motor by means of the pin 17 and the manufacturer is thus assured that there will be no necessity for 55 replacement or repair of motors on this account and no delay caused by the burning out of motors in this manner. It will be evident that the saving of a single motor is sufficient to pay for a great many safety devices of the 60 class described and that the present safety system is therefore highly advantageous in any factory where such metal pins are employed in holding a drive shaft.

While I have illustrated a preferred embodiment of my invention, many modifica-

tions may be made without departing from the spirit of the invention, and I do not wish to be limited to the precise details of construction set forth, but desire to avail myself of all changes within the scope of the 70 appended claims.

Having thus described my invention, what I claim as new and desire to secure by Letters Patent of the United States, is:

1. In a safety system, the combination of an 75 electric motor driven machine having a driven shaft with a supporting framework, said shaft having an aperture and said framework having a registering aperture, a metal member adapted to be received in said apertures 80 for fixedly securing said driven shaft against rotation, supply circuits for energizing said motor, and a normally open electric switch for controlling said supply circuits, said switch being adapted to be closed by the placing of said metal member in predetermined 85 position with respect to said switch whereby the motor cannot be started until said metal member is removed from said apertures and placed in said switch.

2. In a safety system, the combination of an 90 electric motor driven machine having a driven shaft with a supporting framework, said shaft having an aperture and said framework having a registering aperture, a metal 95 member adapted to be received in said apertures for fixedly securing said driven shaft against rotation, supply circuits for energizing said motor, and a normally open electric switch for controlling said supply circuits, 100 said switch being adapted to be closed by the placing of said metal member in predetermined position with respect to said switch whereby the motor cannot be started until said metal member is removed from said apertures and placed in said switch, and means 105 for controlling said motor comprising an electromagnetic switch located in the supply circuit of said motor, a push button switch for closing the circuit through the electromagnet of said switch, an auxiliary contact carried by said electromagnetic switch for shunting said push button switch, and an auxiliary push button for opening the circuit through said electromagnet to effect an 110 opening of said electromagnetic switch.

3. In a safety system, the combination of an 115 electric motor driven machine having a driven shaft with a supporting framework, said shaft having an aperture and said framework having a registering aperture, a metal member adapted to be received in said apertures for fixedly securing said driven shaft against rotation, supply circuits for energizing said motor, a normally open electric 120 switch for controlling said supply circuits, said switch being adapted to be closed by the placing of said metal member in predetermined 125 position with respect to said switch whereby the motor cannot be started until 130

said metal member is removed from said apertures and placed in said switch, said switch being enclosed in a casing having a socket for receiving said metal member to prevent 5 actuation of said switch except by said metal member.

In witness whereof, I hereunto subscribe my name, this 12th day of September, 1931.

JOSEPH M. HADFIELD.
